UNITED STATES PATENT OFFICE.

OLAF NIDLAND PEDERSEN, OF NEW ORLEANS, LOUISIANA.

SCALING DEVICE.

Application filed December 17, 1920. Serial No. 431,355.

To all whom it may concern:

Be it known that I, OLAF N. PEDERSEN, citizen of the United States of America, residing at New Orleans, in the parish of Orleans and State of Louisiana, have invented 5 certain new and useful Improvements in Scaling Devices, of which the following is a specification.

The present invention relates more particularly to scaling devices for removing 10 rust and paint from a ship's hull or other surfaces, or scale from the interior of a boiler.

Among the difficulties encountered in devices of this type are; adaptation of the 15 scraping elements to the surface on which they operate; lack of sufficient flexibility between the driving means and the scraping elements; sudden and irregular strains put 20 upon the driving shaft and connections due to this insufficient flexibility; requirement of more motive power than should be necessary; danger to the operator from flying pieces of broken scrapers; complexity of the 25 parts with consequent frequent disorders; limited use to a narrow field of application; short life for the use of the tool; and high cost of production. The main objects of the 30 present invention are to overcome these and other deficiencies.

Referring to the drawings:—

Fig. 1 is a side elevation of a suitable small motor with the scaler connected, the 35 socket plates being shown in cross section and the open or spread position of the scrapers being shown in dotted lines; and

Fig. 2 is a top plan view of the cap plate.

The motor and its shaft may be of any usual and well known type and mounted in 40 any desired manner.

The scaler comprises a plurality of scaling elements or heads 1 each threaded or otherwise removably secured to the end of a rod 2 the opposite end of which carries a ball 3. 45 The head will be designed and proportioned according to the work it is to do and the surface upon which it is to operate. The same is true of the length of the rods 2. Ball 3 of each rod is seated in a semi-spherical socket 50 4 in a base plate 5; the sockets being disposed eccentrically relatively to the base plate and, preferably, equi-distant from the centre and from each other, circumferentially. Cap plate 6 has sockets 7, substantially complementary to sockets 4 and co-operating therewith. The base plate and

cap plate together, really constitute a head or block containing the sockets of the ball and socket couplings. Communicating with each socket 7 is an opening 8 which extends 60 through the cap plate in the direction of the thickness of the plate. Each opening is circular, as shown in Fig. 2, extends into socket 7 for about a third of its radius, and is parallel to the face of the cap plate. The wall 9 65 of each opening is tapered on an angle of about 30 degrees outwardly from the centre of the combined sockets 4 and 7. Jam nuts 10 may be used for locking the heads against 70 jarring or working loose, as will be readily understood.

In assembling the parts, the balls 3 are seated in sockets 4 and the cap plate 6 is slipped down over rods 2 so that its sockets seat on the upper or outer halves of the balls. 75 With the parts thus assembled, the head or combined plates are slipped onto the end of the driving shaft 11, the outer or connecting end of which is squared or of other non-cylindrical shape, to seat in the cooperating opening 12 which extends centrally through the assembled plates. A nut 13 threaded on the projecting end of 11 clamps the assembled parts to the shaft to rotate therewith, and, at the same time, of course, clamps the base 80 and cap plates together so that their sockets completely and accurately enclose the balls 3. Then, the hammer heads are threaded on or otherwise secured to the ends of their respective rods and the device is ready for 85 use.

It will be noticed that the smallest diameter of each opening in the cap plate is considerably greater than the diameter of rod 2 extending therethrough. Consequently, if the rod is swung to one side until it engages wall 9 and then travels in a complete circle around that wall, its head will describe a circle of correspondingly greater diameter. At the same time, because, of the 100 ball and socket mounting of each rod, the rod is absolutely unhampered in revolving about its longitudinal axis, as will be readily understood. Shaft 11 driven by the motor, revolves at a high rate of speed, rotating the 105 device at a correspondingly high rate. The scaling elements are arranged eccentrically in the plates relatively to the axis of the driving shaft. Due to their ball and socket coupling or connection with the plates, these 110 rods, therefore, are acted upon centrifugally so that they will be spread out circumferen-

tially, as indicated in dotted lines in Fig. 1. But, the only force maintaining them thus spread is centrifugal. Of course, during rotation, the ball ends will, necessarily, be somewhat in advance of the hammer heads so that rods 2 will be inclined both laterally and longitudinally, as will be readily understood. Each head 14 is formed with a series of concentrically disposed spirally shaped scraping edges or blades of any desired configuration. These blades, coming in contact with the surface on which the device is used, due to the inclinations of rods 2 and the rotation of shaft 11, will have a drawing or scraping action, while, at the same time, due to the extremely flexible connections and the centrifugal spreading force, they will have a hammering action as they rebound freely from the surface and are immediately returned by centrifugal force. It will be noticed that they yield freely to a large angle or degree in every direction, not merely circumferentially or radially, or in all but one or two directions. And the amount or degree of this yielding movement in every direction is ample to permit any or all heads to disengage from any point of the surface with which it contacts, the instant there is any considerable resistance offered to the movement of the scraping head. The result is an absolutely uniform resistance put upon the shaft 11, so that the minimum amount of power may be used in the motor and all sudden strains are eliminated, reducing breaks and repairs to the minimum.

Obviously, the lengths of the rods 2, and the type of head will be varied a great deal

to meet the many different requirements of the particular work on which the tool is to be used. Other details of construction may likewise be changed.

Many changes may be made in the construction, arrangement, and disposition of the various parts of the invention within the scope of the appended claim without in any way departing from the field and scope of the invention, and it is meant to include all such.

Having thus described my invention, what I claim and desire to protect by Letters Patent is:

In a rotary scraper, a shaft, a head mounted thereon to turn therewith and provided with a series of equi-distant sockets disposed eccentrically relatively to the axis of rotation of said head, a series of scraping elements having balls located in said sockets respectively and having their other ends free to swing and yield in every direction, the balls of the respective scraping elements being free to turn with a universal motion in said sockets and being held therein always at the same distance radially from the axis of said shaft, the scraping elements spreading under the action of centrifugal force, and in accordance therewith, and traveling in a path defining a cone.

In testimony whereof, I have signed my name to this specification in the presence of two subscribing witnesses.

OLAF NIDLAND PEDERSEN.
